LENS FOR HAZARD WARNING LAMPS, VEHICLE LAMPS AND SIMILAR ARTICLES

Robert E. Dawson, Huntingdon Valley, Pa., assignor to
R. E. Dietz Company, Syracuse, N.Y., a corporation of
New York

Filed Feb. 26, 1962, Ser. No. 68,968

Term of patent 14 years

(Cl. D48—32)

FIGURE 1 is a top plan view of a lens for hazard warning lamps, vehicle lamps and similar articles, showing my new design, it being understood that the partially shown configurational details on the bottom of the lens, which details are visible through the top face of the lens, continue uniformly throughout the lens as indicated in FIGS. 3, 4, and 5;

FIGURE 2 is a side elevational view thereof;

FIGURE 3 is a sectional view on the line 3—3 of FIG. 1;

FIGURE 4 is a sectional view on the line 4—4 of FIG. 1;

FIGURE 5 is a bottom plan view thereof, it being understood that the prisms which are partially shown around the border of the lens continue uniformly throughout said border area; and

FIGURE 6 is an enlarged fragmentary perspective view of the prisms on the border of the lens.

I claim:

The ornamental design for a lens for hazard warning lamps, vehicle lamps and similar articles, substantially as shown and described.
